GIRAFFE FIGURE FOR PLAYGROUND
APPARATUSJohn E. Hill, 21 Sheraton Park, Arlington, Mass. 02172,
and Joseph E. Hill, 221 Mount Auburn St., Cambridge,
Mass. 02139

Filed July 24, 1968, Ser. No. 12,883

Term of patent 14 years

Int. Cl. D21—02

U.S. Cl. D34—2

FIG. 1 is a front perspective view of the giraffe figure for playground apparatus, and

FIG. 2 is a rear perspective view of the giraffe figure for playground apparatus, and

FIG. 3 is an end view of the giraffe figure for playground apparatus.

The characteristic feature of our design resides in the large circular extremities on the horns in combination with the uniformly vertical forefront of the giraffe figure as shown.

We claim:

The ornamental design for giraffe figure for playground apparatus as, shown and described.
